UNITED STATES PATENT OFFICE.

NED E. BARNES, OF WILLIS, TEXAS.

RAIL BRACE.

Application filed June 28, 1922. Serial No. 571,575.

To all whom it may concern:

Be it known that I, NED E. BARNES, a citizen of the United States, residing at Willis, in the county of Montgomery and State of 5 Texas, have invented certain new and useful Improvements in Rail Braces, of which the following is a specification.

The present invention relates to rail braces and has for its principal object to 10 provide a structure which is readily assembled and disassembled and which will efficiently brace the rails and at the same time prevent spreading thereof.

Another important object of the invention 15 is to improve upon devices of this nature by providing a simple and efficient structure, one of which is comparatively inexpensive to manufacture, reliable in operation and well adapted to the purpose for 20 which it is designed.

With the above and numerous other objects in view as will appear as the description progresses, the invention resides in certain novel features of construction, and the 25 combination and arrangement of parts as will be hereinafter more fully described and claimed.

In the drawing:—

Figure 1 is a perspective of a pair of 30 braces embodying my invention,

Figure 2 is a transverse section taken through one of the braces, and

Figure 3 is a detailed section taken on the line 3—3 of Figure 2 looking in the direction of the arrow.

Referring to the drawing in detail it will be seen that each brace consists of an outer jaw 1 which is mounted on a base plate 2 upon which is seated a rail 3. An inner jaw 4 is constructed similar to the outer jaw 1 in that it extends over the base of the rail 3 and is formed integral with the leg 5. An opening 6 extends transversely through the base plate 2 and an opening 7 extends transversely through the leg 5 and these two openings 6 and 7 are adapted to register with each other when the elements are assembled. A tie rod 8 extends between the two braces as is indicated to advantage in

Figure 1 and also extends through the openings 6 and 7 of the two brace members.

This tie rod 8 is provided adjacent each end with a pair of spaced openings 9 having inner straight sides 10 that extend at right angles to the rod and outer slanting sides 11 which extend at obtuse angles from the upper side of the rod 8 when it is in assembled position as is indicated in Figure 2. Suitable wedges 12 co-operate with these openings 9 and each wedge comprises a body 60 portion having an outer slanting side 13 and an inner straight side 14 so that the bottom end of the wedge is substantially smaller than the upper end thereof. Each wedge is also provided with a plurality of 65 apertures 15 for receiving cotter pins or the like so that the same may be locked from accidental removal.

An inspection of the drawing will readily disclose that the tighter the wedges 12 are 70 driven into the openings 9 the tighter will be the clamping action between the jaws 1 and 4 in gripping the rail and it will furthermore be seen that if one wedge is driven further down than the other wedge that is 75 if there is a different level in the tops of the wedges the rail and the corresponding clamp or brace will be shifted to some extent longitudinally of the tie rod so that the distances between the rails 3 may be slightly 80 varied to accommodate the needs in laying tracks as is occasioned from time to time.

Having described the preferred form of my invention with some degree of particularity, it is to be understood that this embodiment has only been shown by way of example and that numerous changes in form, construction, and in the combination and arrangement of parts may be resorted to without departing from the scope of the invention as hereinafter claimed.

Having thus described my invention what I claim as new is:—

In combination, a brace device including 95 a base plate, a jaw extending from and overhanging the base plate, a leg equal in height to the base plate, a jaw extending from the leg and overhanging the base plate

when the brace device is assembled, said base plate and said leg provided with registering apertures, a rod extending through said apertures and provided with a pair of spaced openings, and wedges cooperating with said openings for engaging the base plate and the leg so as to hold the said jaws against a rail resting on the base plate all

in the manner and for the purpose specified.

In testimony whereof I affix my signature 10
in presence of two witnesses.

NED E. BARNES.
